UNITED STATES PATENT OFFICE.

OSCAR A. SMITH, OF EAST CLEVELAND, AND BENJAMIN RINDFLEISCH, OF CLEVELAND, OHIO, ASSIGNORS TO NATIONAL ACME COMPANY, OF CLEVELAND, OHIO, A CORPORATION OF OHIO.

AUTOMATIC THREADING DIE.

Application filed January 17, 1922. Serial No. 529,397.

To all whom it may concern:

Be it known that we, OSCAR A. SMITH and BENJAMIN RINDFLEISCH, citizens of the United States, residing at East Cleveland and Cleveland, respectively, in the county of Cuyahoga and State of Ohio, have invented certain new and useful Improvements in Automatic Threading Dies, of which the following is a specification.

10 This invention relates to threading dies for either stationary or revolving spindles, an object thereof being to provide an improved die mechanism so organized and constructed by virtue of the simplification and interchangeability of the parts as to readily adapt the same for use with either stationary or revolving spindles, whereby the die head comprising the main working parts may be used where heretofore two 20 mechanisms were used.

A further object of this invention is to provide an improved threading die wherein the working parts are so constructed as to enable the same to be hardened and ground 25 practically as well as on a commercially productive basis. As a result of the present improved construction the die head is not only simpler in construction than heretofore but may be practicably hardened and ground so 30 as to enable the same to remain in substantially perfect working condition a considerably longer time than die heads heretofore constructed which it was not practicably possible to harden and grind. Furthermore 35 by virtue of the present invention the die is rendered more efficient and accurate, simpler in construction, more durable in use, and more economical to manufacture.

Other objects of this invention will appear in the following description thereof, reference being had to the accompanying drawings forming a part of this specification wherein like reference characters indicate corresponding parts in the several views and wherein Fig. 1 is a sectional view of a stationary spindle die or hand die embodying my invention; Fig. 2 is a front view thereof partly broken away; Fig. 3 is a sectional fragmentary view illustrating the die in an open position; Fig. 4 is a fragmentary view illustrating the mounting of the adjusting screw and dog; Fig. 5 is a front view partly broken away of the structure indicated in Fig. 6; Fig. 6 is a sectional view of a revolving spindle die embodying my invention; Fig. 7 is a sectional fragmentary view thereof illustrating the die in open or released position; Fig. 8 is a perspective view partly broken away of a revolving spindle die and the operating part thereof; Fig. 9 is a perspective view showing the chaser mechanism for both types of dies; Fig. 10 is a fragmentary perspective view of the cap used for both types of dies; Fig. 11 is a perspective view of the shank for the stationary spindle die; Fig. 12 illustrates the body thereof; Fig. 13 illustrates the adjusting ring thereof; Fig. 14 illustrates the floating thereof; and Fig. 15 illustrates the co-operating handle thereof.

The present invention is an improvement in part over Patent 1,038,670 dated September 17, 1912, and Patent 1,057,014 dated March 25, 1913, granted to Oscar A. Smith, one of the present joint inventors. In each of these patents as a result of the use of a cam disc with its projecting arms located between the chasers or body and the cap or housing of the die, the latter could not readily be made thicker because the diameter of the die could not be practicably increased. Hence neither the cap nor the working parts of the die, with the exception of the chasers and camming portions could be hardened. But by virtue of the present invention the disc is eliminated and the cap itself is provided with the cam faces and hence the cap can be made thicker and at the same time the diameter of the die smaller when desired. On account of the increased thickness of the cap it may be hardened and ground commercially which was not practicable heretofore as the caps have to be so thin that this could not be commercially done. As a consequence of the present improvement the die is not only simplified materially but the cap may be made thicker and hardened and ground, and this without increasing the diameter of the die. Furthermore the die body and cap are so constructed that they may be used interchangeably with either a stationary spindle die or a revolving spindle die, thus eliminating the expense heretofore incident in having two distinct threading dies for cutting threads, one for the stationary spindle and one for the revolving spindle.

The threading tool in the present preferred form herein shown and described comprises a die body 2 of substantially the same construction for both revolving and stationary spindle dies (Figs. 8 and 12). Each die body has a rearwardly extended shank 3 of suitable length, and is provided with a plurality, as four, guides or ways 4 extending radially of the die bodies. The rear portions of these ways are grooved or under-cut at 5 to form recesses, and in the same slide chasers 6, each thereof secured by means of a screw 50 to a guide plate or block 7, the chaser and guide plate having cooperating openings for permitting attachment. Each plate 7 is provided with a projecting pin 9 in position to engage a coiled spring 10 located in a recess or opening 11 in the die body. The guide plates, it will thus be seen, project beyond the two side faces of the chasers into the recesses 8 whereby the chasers are guided in their opening and closing movements and maintained against depthwise movement. Springs 10 are effective to shift the chasers outwardly from the axis of the body, and in practice the projecting pins 9 extend through the plate and fit into openings 12 in the under side of the chasers (see Fig. 1). The outer end of each chaser is tapered circumferentially throughout the major portion thereof as at 13^a but straight in the direction of the axis of the die. In the rear of these straight faces 13^a, the chasers are provided with inclined faces 13.

The die head comprises a cap or housing 14 having a suitable central bore to receive the die body 2, indicated in Figs. 8 and 12, and a suitable distance from the outer face 40 the cap is relief-bored at 15 to remove some of the bearing surface, the cap also having an inwardly extending flange or skirt 16 terminating in a bore. For closing the die chasers suitable stations 17 are machined 45 into the outer face of the cap (see Figs. 2 and 5) and these stations, herein four in number, are milled so as to cooperate with the cammed portions 13^a of the die chasers, the same being equally spaced and those 50 diametrically opposite each other being parallel in alignment. The faces of these stations are straight in the direction of the axis of the die. Curved depressions 18, herein four in number, are also machined in 55 the outer face of the cap adjacent to the milled stations, the same providing clearance for the cammed portions of the chasers. For holding the body and the cap in proper 60 assembled position relative to one another thereby to permit the proper movement of the cap relatively to the chasers, the same is provided with a pair of countersunk openings 19, the shoulders of which are engaged by the heads of screws 20 which project 65 through spacing collars 21 suitably housed

in the inner face of the die body, the screws passing through circular or elongated slots 22 provided in the flange 16 of the cap.

When the die is to be used in a revolving spindle the screws 20 (see Figs. 6 to 8 inclusive) enter tapped holes 23 in the flanged operating spool 24, the latter having a central bore adapted to be housed on the shank 3 of the die body and also having a suitable hub portion 25 which enters the small bore 75 of the die cap. Into the periphery of this spool is machined a suitable groove 26, and through the flanged portion of the spool is machined an elongated slot 27. At right angles to the bore of the spool and centrally located in this slot is housed by means of a bore 28, one end of which is screw-threaded, an adjusting screw or micrometer screw 29, the latter being provided with a groove 80 which is adapted to receive the bifurcated end 30 (Fig. 7) of the adjusting dog or stud 31 located in slot 31^a in the flange of the spool, this stud or dog being carried by the cam operating cap 14. When the die is thus assembled on the revolving spindle, and upon turning the adjusting screw to the right or to the left after loosening screws 20, the cap 14 having the cam face 17, may be adjusted circumferentially.

By virtue of this adjustment the cam operating cap 14 may be rotated or oscillated relatively to the chasers thereby adjusting the chasers relatively to the work by reason of the fact that the tapered cam surfaces 17 of the cap engage with the correspondingly tapered surfaces 13^a of the chasers, this taper being transverse to the axis of the tool.

When the die is to be used in a stationary spindle the screws 20 pass through the elongated slots 22 in the flange 16 of the cap and enter tapped bores 35 in a collar or float-ring 36, the latter being housed on the shank 3 of the body. Through this collar is machined a curved, elongated slot 37 and at right angles to the bore of the collar and centrally located in the slot 37 is housed by means of a bore 38, one end of which is screw-threaded the adjusting or micrometer screw 29. The operation of the adjusting screw upon the collar is substantially the same as hereinbefore described in connection with the spool 24 and hence further description thereof is deemed unnecessary, it being understood that upon adjusting the screw, the cap 14 will be rotated thereby to adjust the cam portions 17 relative to the cam faces 13^a. Located on the shank 3 is a disc 41 carrying in a slotted part thereof a swinging lever 42, the end of which projects into an opening 43 in the shank 3, and to this disc is secured a spindle or rod 44 as by means of screws 45. This spindle or rod is provided with a reduced hub portion 46, projecting into the bore of the shank 3, the spindle or rod, it being understood, constitut- 120 125 130

ing the means for attaching the die to the turret of the machine. Thus, when so attached, the disc or head 41 and the spindle 44 are fixed against movement relatively to each other. The disc 41 is flexibly or resiliently connected to the float-ring 36 by means of screws and cushion springs 47 located in counterbored bores 48 and threaded into openings in the float-ring or collar 36. 10 The purpose and operation of these screws and cushion springs 47 is described in the hereinbefore mentioned Patent No. 1,057,014 and hence a further detailed description thereof is not deemed necessary herein. It 15 will be understood of course that by reason of the construction the entire die head comprising the die body, chasers, cam operating cap 14, and float-ring 36, will all move forward a predetermined distance away from 20 the fixed disc 41 against the action of the cushion springs, after the turret has been stopped, so that at the proper time the springs, having been sufficiently contracted, will pull back the cam cap 14 relatively to 25 the die body and chasers. Thus the cam cap will be shifted to the position shown in Fig. 3 so as to permit the chasers to be opened by their springs 10 in a manner which will be readily understood. The hand lever 42 may 30 be shifted for the purpose of resetting the chasers with relation to the operating cap 14.

The operation of the die (Figs. 6 and 7), when used in connection with a revolving spindle will be readily understood. When 35 the collar 26 is moved forwardly to the position shown in Fig. 6, the cam operating cap 14 closes the die by virtue of the cooperating cam faces 17 and 13 carried by the cap and chasers respectively. When the 40 collar 26 is shifted rearwardly or backwardly, the cam surfaces 17 of the cap 14 recede from the high portions 13^a of the chasers whereupon the springs 10 operate to shift the chasers outwardly and thereby 45 open the die.

The construction of the improved die is such that it is impossible for the die chasers to open while the thread is being cut, even though the die chaser operating means 50 should be, by vibration or otherwise, slightly shifted. Thus, the thread will be cut the full length of the stock without the mutilation of the last thread being cut. In other words, the face 13^a of each chaser, while circumferentially tapered, is however, straight in the direction of the depth of the chaser or of the axis of the die, so that as stated 55 no slight shifting of the parts will affect the position of the chasers. The construction 60 is also such that without increasing the diameter or size of the die the cap or housing can be made thicker and thus permit it to be readily hardened and ground and itself carry the cam surfaces adapted to cooperate 65 with the chasers instead of as heretofore,

necessitating the use of independent parts located within the housing for this purpose, whereby not only are certain parts and the cost thereof eliminated so that the structure of the die and its operation are much simplified, but a number of principal parts can be interchangeably used, either to make up a die adapted for a stationary spindle, or one for a revolving spindle, thus doing away with the necessity of having two distinct 75 and complete dies on hand at all times.

We claim as our invention:

1. A threading die comprising a body member, a plurality of shiftable chasers carried by said member, and a sliding housing member axially slidable for controlling said chasers, said die having means for detachably connecting a stationary or rotary operating means in operative relation to said housing. 80

2. A threading die comprising a shank having an enlarged head or body member, a plurality of shiftable chasers carried by said head, and a sliding housing member having cam surfaces engageable with said chasers upon axial sliding movement of the housing member, said die having means for detachably connecting a stationary or rotary operating means in operative relation to said housing member. 85

3. A threading die comprising a shank having an enlarged head or body member, a plurality of shiftable chasers carried by said head, an axially shiftable housing member having means for controlling said chasers, and an operating sleeve detachably connected to said housing member. 100

4. A threading die comprising a shank adapted to be attached to a stationary or rotary spindle and having an enlarged head, radially shiftable chasers carried by said head, a housing cap having a part slideable over said head, an operating sleeve, and detachable means for interconnecting said head, cap and sleeve, and permitting relative 105 axial movement thereof.

5. A threading die comprising a shank adapted to be attached to a stationary or rotary spindle and having an enlarged head, radially shiftable chasers carried by said head, a housing cap having a part slideable over said head, and having a radially extending flange in rear of said head, an operating sleeve, and detachable means for 115 interconnecting said head, flange of the cap, and sleeve, and permitting relative axial movement thereof.

6. A threading die comprising a shank adapted to be attached to a stationary or rotary spindle and having an enlarged head, radially shiftable chasers carried by said head, a housing cap having a part slideable over said head, an operating sleeve, and detachable means for interconnecting said 120 head, cap and sleeve, and permitting relative 125 axial movement thereof.

- 4
- axial movement thereof, said means having a slidable connection with said head, a fixed detachable connection with said sleeve, and a circumferential adjustable connection with 5 said cap flange.
7. A threading die comprising a shank adapted to be attached to a stationary or rotary spindle and having an enlarged head, radially shiftable chasers carried by said 10 head, a housing cap having a part slidable over said head, an operating sleeve, and detachable means for interconnecting said head, cap and sleeve, and permitting relative axial movement thereof, said cap having a 15 part thereof shiftable into direct engagement with said chasers.
8. A threading die comprising a shank having an enlarged head, radially shiftable chasers carried by said head, a housing member 20 embracing said head, means for shifting said housing member and head axially one relatively to the other for controlling the chasers, and means for adjusting said housing member circumferentially relatively to 25 the chasers.
9. A threading die comprising a shank having an enlarged head, radially shiftable chasers carried by said head, a housing member 30 embracing said head, means for shifting said housing member and head axially one relatively to the other for controlling the chasers, and means for adjusting said housing member circumferentially relatively to 35 the chasers, said adjusting means having connection with said first mentioned means.
10. A threading die comprising a shank having an enlarged head, radially shiftable chasers carried by said head, a housing member 40 embracing said head, means for shifting said housing member and head axially one relatively to the other for controlling the chasers, and means for adjusting said housing member circumferentially relatively to 45 the chasers, said adjusting means having connection with said first mentioned means, and said housing member having cam surfaces at the outer end thereof adapted to directly engage the chasers.
11. A threading die comprising a shank 50 having an enlarged head, radially shiftable chasers carried by said head, a housing member having a part thereof provided with an internal face of substantially the same diameter as the outer face of said head and embracing the same, and also having a radially 55 extending flange in rear of said head, means for shifting said housing member axially over said head for controlling the chasers, and means extending through said flange 60 for detachably connecting said first means and said head.
12. A threading die comprising a shank having an enlarged head, radially shiftable chasers carried by said head, a housing member 65 having a part thereof provided with an internal face of substantially the same diameter as the outer face of said head and embracing the same, and also having a radially extending flange in rear of said head, means for shifting said housing member axially over said head for controlling the chasers, and means extending through said flange for detachably connecting said first means and said head.
13. A threading die comprising a body member, shiftable chasers carried thereby, a housing member embracing said body member, means for shifting said housing member and body member one relatively to the other for controlling the chasers, and means for adjusting said housing member and body member circumferentially one relatively to 80 the other.
14. A threading die comprising a body member, shiftable chasers carried thereby, a housing member embracing said body member, means for shifting said housing member and body member one relatively to the other for controlling the chasers, and means for adjusting said housing member and body member circumferentially one relatively to 85 the other.
15. A threading die comprising a body member, shiftable chasers carried thereby, a housing member embracing said body member, means for shifting said housing member and body member one relatively to the other for controlling the chasers, and means for 90 detachably connecting said last means and housing member.
16. A threading die comprising a body member, shiftable chasers carried thereby, a housing member embracing said body member, means for shifting said housing member and body member one relatively to the other for controlling the chasers, and means for 95 detachably connecting said last means, housing member, and body member.
17. A threading die comprising a body member, radially shiftable chasers carried thereby, a housing member embracing said body member, operating means for shifting the housing and body members one relatively to the other to control the chasers, and means for slidably connecting said operating 115 means and body member.
18. A threading die comprising a shank having an enlarged head, chasers carried by the head, an axially shiftable housing cap embracing the head, and means for shifting the cap and comprising an operating sleeve mounted in rear of the cap and formed independently thereof, said cap being hardened to directly engage the chasers for operating them.

19. A threading die comprising a body member and a plurality of shiftable chasers carried thereby, and an axially shiftable housing member therefor, said housing member being hardened to directly engage the chasers for operating them. 21. A threading die comprising a body member, a plurality of radially shiftable chasers carried thereby, a housing cap hardened for engagement with the chasers, and means for shifting the cap axially relatively to the chasers, and means for shifting the cap circumferentially relatively to the chasers. 15
20. A threading die comprising a body member, a plurality of radially shiftable chasers carried thereby, a housing cap hardened for engagement with the chasers, and means for shifting said cap in a plurality of directions relatively to the chasers. 20
- Signed at Cleveland, Ohio, this 6th day of January, 1922.
